TEXTILE BLEACHING COMPOSITION

Wilhelminus J. C. Viveen and Cornelis U. Kloosterman, Deventer, Netherlands, assignors to Koninklijke Industriële Maatschappij voorheen Noury & van der Lande N.V., Deventer, Netherlands, a corporation of the Netherlands

No Drawing. Filed June 2, 1960, Ser. No. 33,397
Claims priority, application Great Britain, June 19, 1959, 21,220/59; July 29, 1959, 26,061/59; Oct. 13, 1959, 34,695/59; Netherlands, June 6, 1959, 239,952
5 Claims. (Cl. 252—98)

This invention relates to a washing and/or bleaching composition containing, in addition to an active oxygen releasing compound, an activator for this compound, and further to a process of washing and bleaching textiles with the aid of such compositions, and further to certain novel activator compounds for use in said compositions.

It is an object of this invention to provide washing and bleaching compositions containing active oxygen releasing compounds and activators for such compounds.

It is a further object of this invention to provide certain novel compounds and mixtures of said compounds for use as activators for active oxygen releasing compounds in washing and bleaching compositions.

It is a further object of this invention to provide a process for producing said novel activator compounds.

It is a further object of this invention to provide said activator compounds in a coated form to enhance the activity and stability of said compounds.

Further objects and attendant advantages of this invention will become apparent from the following more detailed description.

The term "textiles" as used throughout the specification is intended to include natural and synthetic fibres as well as products manufactured therefrom or therewith.

It is well-known that on washing and/or bleaching textiles use is made of agents containing active oxygen releasing compounds having a bleaching effect on the textiles to be treated. As the active oxygen releasing compounds, inorganic persalts such as perborates, percarbonates, perphosphates, persilicates, persulphates and, moreover, hydrogen peroxide and sodium peroxide are used.

However, washing and/or bleaching agents containing such active oxygen releasing compounds generally have the disadvantage that their bleaching effect is relatively low at temperatures below 85° C. which gives rise to difficulties when these agents are used in machines for household purposes in which the temperature of the wash-water is not higher than about 70° C.

It has already been proposed to enhance the effect of a washing and/or bleaching agent containing an active oxygen releasing compound by adding thereto particular substances, so-called "activators." Definite quantities of organic acid anhydrides, for instance, have been added to washing and bleaching agents containing active oxygen releasing compounds. However, in practice, this measure does not yield the desired result, as the reactivity of most acid anhydrides appears to be insufficient in this respect.

It has also been proposed to add formamide and representatives of the nitrile group to washing agents containing active oxygen releasing compounds. However, formamide is a liquid and it is difficult to incorporate it into a washing powder. The result obtained by adding formamide or nitriles is moreover very small.

Now it has been found that if a compound containing one or more nitrogen atoms having at least two acyl groups attached to the same nitrogen atom or a mixture of such compounds is added to a washing and/or bleaching agent of the usual composition containing an active oxygen releasing compound, a composition is obtained which

2

is highly efficient for the washing and/or bleaching treatment of textiles at a temperature below boiling temperature.

Consequently, this invention relates in part to a washing and/or bleaching composition containing besides an active oxygen releasing compound an activator for this compound and is characterized in that a compound containing one or more nitrogen atoms having at least two acyl groups attached to the same nitrogen atom or a mixture of such compounds, is used as the activator.

The bleaching effect of the compositions according to the invention is, when using them at temperatures below boiling temperature, especially at temperatures between 15 and 85° C., not only considerably better than the effect obtained at the same temperature with compositions not containing an activator according to the invention, but furthermore also greater than the effect of compositions without activators at boiling temperature. Moreover, the compositions according to the invention cause considerably less loss in strength of the fibres, do not significantly affect cellulose and synthetic fibres such as polyamide fibres, while furthermore the drawbacks associated with the use of the agents hitherto known for washing coloured material are practically fully eliminated, especially as regards the attack of the colour, if the agents according to the invention are used for this purpose. Apart from this, the compositions according to the invention are particularly effective for washing cotton goods, as this material even if washed several times keeps a high degree of lightness and does not easily become yellow. The bleaching compositions according to the invention and especially the compositions containing perborate possess, moreover, the additional advantage that with a favourable ratio of perborate and activator an over-bleaching is not possible. Furthermore, these bleaching compositions are excellently suitable for addition to the rinsing bath.

As activators for oxygen releasing compounds according to this invention there are included: N-diacylated amines, e.g., diacetyl methylamine, diacetyl ethylamine, diacetyl propylamine, diacetyl butylamine, diacetyl benzylamine and diacetyl aniline; N-diacylated ammonia, e.g., diacetamide, dipropionamide; N-diacylated amides, e.g., N-formyldiacetamide, N-acetyl diacetamide, (triacetamide), N-propionyldiacetamide, N-butyryldiacetamide, N-valeryldiacetamide, N-caproyldiacetamide, di-carboxylic acid acyl imides, e.g., N-acetyl phthalimide, N-acetyl succinimide; N,N-diacyl cyanamide; N-diacylated urethanes, e.g., N,N-diacyl ethylurethane, N-acetyl, N-propionyl ethylurethane; N-diacylated hydrazines, e.g., triacetylhydrazine, tetra-acetylhydrazine, tripropionylhydrazine, N,N-diacyl-N'-benzoylhydrazine and N,N-diacyl-N'-isopropylidenehydrazine; N-diacylated alkylene diamines, e.g., triacetyl methylene diamine, tetra-acetyl methylene diamine, tetra-acetyl ethylene diamine, tetra-acetyl hexamethylene diamine and tetra-acetyl phenylene diamine, the N-diacyl compounds of semicarbazide, thiosemicarbazide and dicyanodiamide.

The favourable properties mentioned above of the washing and/or bleaching agents according to the invention may surprisingly still be improved to a large extent, if the activator according to the invention is covered with a solid material soluble in the washing and/or bleaching liquid. As such, stearic acid, polyethyleneglycol such as, e.g., Carbowax 4000 and 6000 (Carbowax is a registered trademark in the name of Union Carbide Corporation relating to polyethylene glycols. Carbowax 4000 and 6000 is the designation given solid polyethylene glycols having respectively an average molecular weight of 3000-3700 and 6000-7500). Furthermore condensation products of ethyleneoxide and propyleneoxide may be used. More par-

ticularly those compounds having a useful function in the suds, such as, e.g., polyvinylalcohol, carboxymethylcellulose, cetylalcohol and fatty acid alkanolamides, are especially suitable. Moreover, by this means the shelf life, especially of the finished powders, is enhanced.

It is recommended to granulate the activator before covering.

Covering may be effected in coating-pans suitable to the purpose. The covering material dissolved in water or in an organic solvent, is sprayed on the activator in finely divided form, after which the covered material is dried. Solutions of stearic acid, "Carbowax" or C_{12} - C_{14} isopropanolamide in isopropanol as well as solutions of polyvinylalcohol and carboxymethylcellulose in diluted ethanol are very suitable. As to the quantity of the covering to be used, it is in general sufficient to apply 1 to 30% by weight on the activator.

Washing and/or bleaching of textiles may be effected with the aid of a liquid containing the finished products according to the invention.

However, it is also possible to execute this treatment with a washing or bleaching liquid to which one or more activators have been added, just prior to the treatment or during the same.

In any case very good results are obtained with a treatment temperature below boiling temperature, preferably however with a temperature between 15 and 85° C.

As activators for the active oxygen releasing compound in a washing and/or bleaching agent there have been found especially effective the hitherto unknown compounds with the general formula

in which R_1 represents a hydrogen-atom or a $COCH_3$ group.

These new compounds according to the invention, or mixtures thereof, may be obtained by either of the following two methods.

Thus it is possible to prepare N,N,N',N' -tetraacetylmethylenediamine by allowing to react ketene on a mixture of N,N' -diacetylmethylenediamine and an inert solvent in the presence of an acid-reacting catalyst.

This reaction may be executed in benzene as an inert solvent at a temperature of 30-80° C., preferably however at a temperature of 50-65° C., in the presence of 0.5-3%, preferably of 2% by weight of p-toluenesulphonic acid calculated on N,N' -diacetylmethylenediamine. The N,N,N',N' -tetra-acetylmethylenediamine formed may be recovered from the reaction mixture in any conventional way.

According to the invention, N,N,N',N' -tetra-acetylmethylenediamine may, however, also be obtained by acetylation of N,N' -diacetylmethylenediamine with the aid of acetic acid anhydride while eliminating continuously the acetic acid formed during the reaction, e.g., by distillation.

If during the reaction between diacetylmethylenediamine and acetic acid anhydride, the acetic acid liberated is not eliminated from the reaction mixture, mainly N,N,N' -triacetylmethylenediamine is formed.

When only part of the quantity of acetic acid that theoretically could be formed during the acetylation is eliminated from the reaction mixture, mixtures are obtained that appear to contain triacetylmethylenediamine and tetra-acetylmethylenediamine with the quantity of the former increasing as less acetic acid is eliminated.

The following examples are presented to further illustrate the invention, and should not be considered as limiting thereof.

EXAMPLE I

Pieces of cotton fabric were soiled with the juice of black currants, by evenly applying to them 2.7 cc. of black currant juice per 100 cm.² of surface of cotton fabric

by means of a brush. After being dried in the air, the lightness of the fabric was measured with a photoelectric remission meter. It was 29% of the lightness of magnesium oxide.

5 Parts of the pieces of material were washed for 15 minutes at 60° in suds of the following composition:

	G./l.
Sodium salt of dodecyl benzene sulphonic acid	0.85
Lauryl isopropanolamide	0.10
Tetrasodium pyrophosphate	0.75
Pentasodium tripolyphosphate	0.60
Alkaline water-glass ($Na_2O/SiO_2=1/2$)	0.20
Na CMC (100%) (sodium carboxymethylcellulose)	0.04
15 Sodium sulphate	0.80
Sodium perborate-tetrahydrate (10.2% active oxygen)	0.50

The percentage of lightness of the washed pieces of material amounted to 64 (lightness of magnesium oxide=100 units), which is 13 units higher than the percentage of lightness of the pieces of material after thorough rinsing with water, which was 51.

Other parts of the material were washed in three samples of suds of the same composition, to which respectively 25 0.1, 0.4 and 0.5 g./l. of tetra-acetyl hydrazine was added. These suds contained per atom of active oxygen from the perborate 0.63, 2.50 and 3.14 acetyl groups as tetra-acetyl hydrazine, respectively.

The percentages of lightness of the thus washed material were respectively 20, 31 and 34 units higher than the percentage of lightness of the material which was only thoroughly rinsed with water. The relative improvements by adding tetra-acetyl hydrazine in the concentrations mentioned were therefore 54%, 138% and 35 162%.

EXAMPLE II

Pieces of the same kind of fabric, soiled with black currant juice, as used in Example I, were washed for 40 15 minutes at 60° C. in suds of the following composition:

	G./l.
Sodium soap	3.1
Sodium carbonate	1.00
45 Neutral water-glass ($Na_2O/SiO_2=1/3.3$)	0.17
Sodium perborate-tetrahydrate (9.9% of active oxygen)	0.68

The percentage of lightness of the material was increased to 62% by washing (lightness of magnesium oxide=100 unit); this is 11 units higher than the lightness obtained by only rinsing the material thoroughly with water.

If the suds also contained 0.42 g./l. of tetra-acetyl hydrazine, the percentage of lightness of the material was 55 increased to 73, which is 22 units more than the percentage of lightness obtained after thoroughly rinsing with water only. The relative improvement by adding tetra-acetyl hydrazine therefore amounted to 100%. In this case, the number of acetyl groups added to the suds as tetra-acetyl hydrazine was 2.0 per atom of active oxygen from the perborate.

EXAMPLE III

A detergent in powder form had the following composition:

20.0% of sodium salt of dodecyl-(tetrapropylene)-benzene sulphonic acid	
16.0% of tetrasodium pyrophosphate	
16.0% of pentasodium tripolyphosphate	
4.8% of neutral water-glass ($Na_2O/SiO_2=1/3.3$)	
2.0% of sodium salt of carboxymethylcellulose	
27.6% of sodium sulphate	
13.6% of water	
75	100.0%

100 parts by weight of this powder were mixed with 8 parts by weight of sodium perborate-tetrahydrate and 6.25 parts by weight of tetra-acetyl hydrazine (STAH mixture).

A solution was prepared, containing 5.70 g./l. of the STAHL mixture and pieces of the same kind of material stained with fruit juice, as used in Example I, were washed in this solution for 15 minutes at 60° C.

The material was then rinsed three times, ironed with a hot iron and the lightness was measured with a Hunter photoelectric remission meter.

With this test, a similar test was carried out with a mixture of 100 parts by weight of the afore-mentioned powder and 8 parts by weight of sodium perborate-tetrahydrate without tetra-acetyl hydrazine (mixture SO). 5.4 grams per litre solution were used of this mixture.

The lightness of the material washed with STAHL mixture was 27 units higher than the lightness of material thoroughly rinsed with water only (51 units).

In the case of the SO mixture, this difference in lightness was 12 units (lightness of magnesium oxide=100 units).

So by using a quantity of tetra-acetyl hydrazine such as to correspond to 2.5 bound acetyl groups per atom of active oxygen, a relative improvement of 125% was obtained.

EXAMPLE IV

100 parts by weight of the powder described in Example III were mixed with 8 parts of sodium perborate-tetrahydrate and 6.60 parts of triacetyl hydrazine (STrAH mixture).

A solution was prepared containing 5.75 g. per litre of this STrAH mixture and the same washing test was carried out with it as described in Example III.

The lightness of the material was 22 units higher than the lightness of the material rinsed with water thoroughly (51 units). In the case of the SO mixture, this difference in lightness was 12 units.

So the relative improvement in this case, where 2.5 bound acetyl groups per atom of active oxygen were used, was 83%.

EXAMPLE V

100 parts by weight of the powder described in Example III were mixed with 8 parts of sodium perborate-tetrahydrate and 11.0 parts of tripropionyl hydrazine (STrPrH mixture).

A solution was prepared, containing 5.95 g. per litre of this STrPrH mixture and a similar washing test was carried out with it as described in Example III, except that in this case the experiment was carried out at 50° C.

The lightness of the washed material was 23 units higher than the lightness of material rinsed thoroughly with water (51 units). In the case of the SO mixture, this difference in lightness was 12 units.

So the relative improvement in this case, where 3.3 bound propionyl groups per atom of active oxygen were used, was 92%.

EXAMPLE VI

100 parts by weight of the powder described in Example III were mixed with 8 parts of sodium perborate-tetrahydrate and 7.05 parts of tetra-acetylene diamine (STAED mixture).

A solution was prepared, containing 5.75 g. per litre of this STAED mixture and a similar washing test was carried out with it as described in Example III, except that another lot of cotton fabric, soiled with black currant juice, was used.

The lightness of the washed material was 23 units higher than the lightness of material rinsed thoroughly with water (51 units). In the case of the SO mixture, this difference in lightness was 13 units.

So the relative improvement in this case, where 2.5

bound acetyl groups per atom of active oxygen were used, was 77%.

EXAMPLE VII

100 parts by weight of the powder described in Example III were mixed with 8 parts of sodium perborate-tetrahydrate and 6.31 parts of diacetamide (SDAA mixture).

A solution was prepared, containing 5.72 g. per litre of this SDAA mixture and a similar washing test was carried out with it as described in Example VI.

The lightness of the washed material was 22 units higher than the lightness of material rinsed thoroughly with water (51 units). In the case of the SO mixture, this difference in lightness was 13 units.

So the relative improvement in this case, where 2.5 bound acetyl groups per atom of active oxygen were used, was 69%.

EXAMPLE VIII

100 parts by weight of the powder described in Example III were mixed with 8 parts of sodium perborate-tetrahydrate and 5.96 parts of triacetamide (STrAA mixture).

A solution was prepared containing 5.70 g. per litre of this STrAA mixture and a similar washing test was carried out with it as described in Example VI.

The lightness of the washed material was 30 units higher than the lightness of material rinsed thoroughly with water (51 units). In the case of the SO mixture, this difference in lightness was 13 units.

So the relative improvement in this case, where 2.5 bound acetyl groups per atom of active oxygen were used, was 131%.

EXAMPLE IX

35 A detergent in powder form had the following composition:

43% of sodium soap
25% of sodium carbonate
3% of neutral water-glass
29% of water

100%

45 100 parts by weight of this powder were mixed with 7.5 parts by weight of sodium perborate-tetrahydrate and 6.70 parts by weight of diacetylpropylamine (ZDAPrA mixture).

50 A solution was prepared containing 9.14 g. per litre of this ZDAPrA mixture and pieces of the same kind of material soiled with fruit juice, as used in Example I, were washed in this solution for 15 minutes at 50° C.

The material was then rinsed three times, ironed with a hot iron and the lightness was measured with a Hunter photo-electric remission meter.

55 With this test, a similar test was carried out with a mixture of 100 parts by weight of the afore-mentioned powder and 7.5 parts by weight of sodium perborate-tetrahydrate without diacetyl propylamine (ZO mixture). 8.60 grams per litre of this mixture were used.

60 The lightness of the material washed with the ZDAPrA mixture was 19 units higher than the lightness of material thoroughly rinsed with water only (51 units).

In the case of the ZO mixture, this difference in lightness was 12 units (lightness of magnesium oxide=100 units).

65 So by using a quantity of diacetyl propylamine such as to correspond to 2.0 bound acetyl groups per atom of active oxygen, a relative improvement of 58% was obtained.

EXAMPLE X

70 100 parts by weight of the powder described in Example IX were mixed with 7.5 parts by weight of sodium perborate-tetrahydrate and 8.35 parts by weight of diacetanilide (ZDAAL mixture).

A solution was prepared containing 9.30 g. per litre of

this ZDAAL mixture and a similar washing test was carried out with it as described in Example IX.

The lightness of the material washed with the ZDAAL mixture was 23 units higher than the lightness of material thoroughly rinsed with water only (51 units). In the case of the ZO mixture, this difference in lightness was 12 units.

So the relative improvement in this case, where 2.0 bound acetyl groups per atom of active oxygen were used, was 92%.

EXAMPLE XI

A similar washing test, as described in Example I, was carried out using suds containing 513 mg. N-ethylidiacetamide per litre instead of tetra-acetyl hydrazine.

The relative improvement as to the lightness of the washed material was in the case, where 2.5 bound acetyl groups per atom of active oxygen were used, 125%.

EXAMPLE XII

A similar washing test as described in Example II was carried out using suds containing 724 mg. N,N-diacetyl urethane per litre instead of tetra-acetyl hydrazine.

The relative improvement as to the lightness of the washed material, was in this case, where 2.0 bound acetyl groups per atom of active oxygen were used, 41%.

EXAMPLE XIII

A similar washing test as described in Example I was carried out using suds containing 753 mg. N-acetyl phthalimide per litre instead of tetra-acetyl hydrazine.

The relative improvement, as to the lightness of the washed material, was in the case, where 1.25 bound acetyl groups per atom of active oxygen were used, 136%.

EXAMPLE XIV

Pieces of cotton fabric were soiled as described in Example I. After drying in the air, rinsing thoroughly with water and drying again, the lightness of the pieces of fabric, measured with a photo-electric remission meter was 53% of the lightness of magnesium oxide freshly condensed from the atmosphere.

Seven lots of these pieces of material were washed for 10 minutes at 60° C. in seven different suds.

All these suds contained:

	G./l.
Sodium salt of dodecyl benzene sulphonic acid	0.85
Lauryl isopropanolamide	0.10
Tetrasodium pyrophosphate	0.75
Pentasodium tripolyphosphate	0.60
Alkaline water-glass ($\text{Na}_2\text{O}/\text{SiO}_2 = 1/2$)	0.20
NaCMC (100%) (sodium carboxymethylcellulose)	0.040
Sodium sulphate	0.80

All concentrations refer to the anhydrous substances.

Further components of the different suds were as follows.

G./l.

Suds 1: Sodium perborate (10.0% active oxygen) - 0.52

Suds 2:
Sodium perborate - 0.50
N,N'-tetra-acetylethylene-diamine (herein after referred to as TAMD) - 0.40

Ratio $\frac{\text{bound acetyl groups}}{\text{atoms active oxygen}} = 2.4$

Suds 3:
Sodium perborate - 0.40
TAMD - 0.40

Ratio $\frac{\text{bound acetyl groups}}{\text{atoms active oxygen}} = 3.0$

Suds 4:
Sodium perborate - 0.40
TAMD - 0.30

Ratio $\frac{\text{bound acetyl groups}}{\text{atoms active oxygen}} = 2.25$

Suds 5:

Sodium perborate	0.30
TAMD	0.40
Ratio $\frac{\text{bound acetyl groups}}{\text{atoms active oxygen}}$	= 4.0

Suds 6:

Sodium perborate	0.30
TAMD	0.30
Ratio $\frac{\text{bound acetyl groups}}{\text{atoms active oxygen}}$	= 3.0

Suds 7:

Sodium perborate	0.20
TAMD	0.30
Ratio $\frac{\text{bound acetyl groups}}{\text{atoms active oxygen}}$	= 4.4

After washing, rinsing and drying, the lightness of the 20 pieces of material was measured.
The results were:

Suds No.	1	2	3	4	5	6	7
25 Lightness (percent of MgO)	62	81	79	79	76	76	71.5
Difference with the washing-test without TAMD	0	19	17	17	14	14	9.5
30 Relative improvement, percent	0	210	190	190	155	155	105

The relative improvement is expressed as percentages of the difference in lightness between the pieces of material washed with 0.52 g./l. perborate without TAMD, and the pieces of material only rinsed with water (lightness 53%).

In spite of the very considerable decrease in perborate content of some of the suds, great improvements in bleaching effect were obtained when TAMD was added to the 40 suds.

EXAMPLE XV

A detergent in powder form was made up having the following composition:

45 50% of sodium soap,
16% of sodium carbonate,
3% of neutral water-glass,
31% of water.

50 Subsequently five mixtures were prepared, namely:

Mixture 1:

90 parts by weight of above-mentioned detergent
10 parts by weight of sodium perborate (9.7% active oxygen)

Mixture 2:

85.9 parts by weight of above mentioned detergent
8.6 parts by weight of sodium perborate
5.5 parts by weight of TAMD

60 Ratio $\frac{\text{bound acetyl groups}}{\text{atoms active oxygen}} = 2.0$

Mixture 3:

87.1 parts by weight of above-mentioned detergent
8.7 parts by weight of sodium perborate
4.2 parts by weight of TAMD

Ratio $\frac{\text{bound acetyl groups}}{\text{atoms active oxygen}} = 1.5$

Mixture 4:

88.5 parts by weight of above-mentioned detergent
5.8 parts by weight of sodium perborate
5.7 parts by weight of TAMD

75 Ratio $\frac{\text{bound acetyl groups}}{\text{atoms active oxygen}} = 3.0$

Mixture 5:

91.0 parts by weight of above-mentioned detergent
4.6 parts by weight of sodium perborate
4.4 parts by weight of TAMD

$$\text{Ratio } \frac{\text{bound acyl groups}}{\text{atoms active oxygen}} = 3.0$$

These mixtures were used in concentrations of 6.9; 7.2; 7.1; 7.0 and 6.8 g./l. respectively.

In this way, the following concentrations were obtained (in g./l.).

Mixture No.	1	2	3	4	5
Sodium soap	3.1	3.1	3.1	3.1	3.1
Sodium carbonate	1.0	1.0	1.0	1.0	1.0
Neutral water-glass	0.19	0.19	0.19	0.19	0.19
Sodium perborate	0.69	0.62	0.62	0.41	0.31
TAMD	0	0.40	0.30	0.40	0.30

Five lots of pieces of cotton material, soiled with the same black currant juice as in Example XIV, were washed in these suds for 10 minutes at 60° C. After washing, rinsing and drying, the lightness of the pieces of material was measured, which gave the following results:

Mixture No.	1	2	3	4	5
Lightness (percent of MgO)	62.5	75	66.5	70	65.5
Difference with the washing-test without TAMD	0	12.5	4.0	7.5	3.0
Relative improvements, percent	0	208	67	125	3

The relative improvement is expressed as percentages of the difference in lightness between the pieces of material washed with 0.69 g./l. of perborate without TAMD (mixture 1) and the pieces of material only rinsed with water (lightness 56.5).

In spite of the very considerable decrease in perborate

A detergent was made up having the following composition:

	Percent
Sodium salt of dodecyl benzene sulphonic acid	22.4
5 Lauryl isopropanolamide	2.6
Tetrasodium pyrophosphate	20.0
Pentasodium tripolyphosphate	15.8
Alkaline water-glass ($\text{Na}_2\text{O}/\text{SiO}_2 = \frac{1}{2}$)	5.1
Sodium carboxymethylcellulose (NaCMC) (100%)	1.0
10 Sodium sulphate	21.0
Water	12.1

Subsequently four mixtures were prepared, namely:

Mixture 1:

15	85.5 parts by weight of above-mentioned detergent
	14.5 parts by weight of sodium pyrophosphate perhydrate (8.05% active oxygen)

Mixture 2:

20	77.9 parts by weight of above-mentioned detergent
	13.2 parts by weight of sodium pyrophosphate perhydrate
	8.9 parts by weight of TAMD

Mixture 3:

25	91.2 parts by weight of above-mentioned detergent
	8.8 parts by weight of sodium percarbonate (14.6% active oxygen)

Mixture 4:

30	82.7 parts by weight of above-mentioned detergent
	7.8 parts by weight of sodium percarbonate
	9.5 parts by weight of TAMD

These mixtures were used in concentrations of 4.45, 4.88, 4.16 and 4.59 g./l. respectively. To each of the suds, a quantity of oxygen bleaching agent was added which corresponded to 52 mg./l. of active oxygen.

35 All suds contained the components of the original detergent in the same concentrations.

For the TAMD-containing mixtures 2 and 4, the ratio was:

$$40 \quad \frac{\text{Bound acyl groups}}{\text{Atoms active oxygen}} = 2.5$$

After washing, rinsing and drying, the lightness of the 45 pieces of material was measured.

The results were:

Mixture No.	1	2	3	4
Oxygen releasing substance	Pyrophosphate perhydrate.	Pyrophosphate perhydrate.	Percarbonate.	Percarbonate.
Addition	TAMD	TAMD	TAMD.	TAMD.
Lightness (percent of MgO)	62	80	61	79
Difference with the washing-test without TAMD	0	18	0	18
Relative Improvement	0	190%	0	212%

content of some of the suds, great improvements in bleaching effect were obtained when TAMD was added to the suds.

EXAMPLE XVI

Pieces of cotton fabric were soiled with the juice of black currant as described in Example I. After drying in the air, rinsing thoroughly with water and drying again, the lightness of the pieces of fabric, measured with a photo-electric remission meter, was 52.5% of the lightness of magnesium oxide freshly condensed from the atmosphere.

Two lots of these pieces of material were washed for 10 minutes at 60° C. in four different suds, prepared in the following way:

65 The relative improvement caused by TAMD is expressed as a percentage of the difference in lightness between the pieces of material washed with the mixture containing the same oxygen bleaching agent without TAMD, and the pieces of material only rinsed with water (lightness 52.5).

EXAMPLE XVII

70 A detergent in powder form had the following composition:

50.7% of sodium soap
16.1% of sodium carbonate
2.8% of neutral water-glass
75 30.4% of water

Subsequently four mixtures were prepared, namely:

Mixture 1:

88 parts by weight of above-mentioned detergent
12 parts by weight of sodium pyrophosphate perhydrate (8.1% active oxygen)

Mixture 2:

82.6 parts by weight of above-mentioned detergent
11.3 parts by weight of sodium pyrophosphate perhydrate
6.1 parts by weight of TAMD

Mixture 3:

93 parts by weight of above-mentioned detergent
7 parts by weight of sodium percarbonate (14.6% active oxygen)

Mixture 4:

87 parts by weight of above-mentioned detergent
6.6 parts by weight of sodium percarbonate
6.4 parts by weight of TAMD

For the TAMD-containing mixtures 2 and 4, the ratio was:

$$\frac{\text{Bound acyl groups}}{\text{Atoms active oxygen}} = 2.0$$

These mixtures were used in concentrations of 6.9, 7.35, 6.53 and 6.98 g./l. respectively. To each of the suds, a quantity of oxygen bleaching agent was added which corresponded to 67 mg./l. active oxygen.

All suds contained the components of the original detergent in the same concentrations.

Four lots of pieces of cotton material stained with the same black currant juice as described in Example I were washed in these suds for 10 minutes at 60° C. After washing, rinsing and drying, the lightness of the pieces of material was measured, which gave the following results:

Mixture No.....	1	2	3	4
Oxygen releasing substance.	Pyrophosphate perhydrate.	Pyrophosphate perhydrate.	Percarbonate.	Percarbonate.
Addition.		TAMD.		TAMD.
Lightness (percent of MgO).	62.	78.	60.5.	73.
Difference with the washing-test without TAMD.	0.	16.	0.	12.
Relative improvement.	0.	200%.	0.	192%.

The relative improvement caused by TAMD is expressed as percentages of the difference in lightness between the pieces of material washed with the mixture containing the same oxygen bleaching agent without TAMD, and the pieces of material only rinsed with water (lightness 54%).

EXAMPLE XVIII

Three comparative washing tests, substantially as described in Example I were carried out using suds containing 0.39 g. sodium perborate (10.2% active oxygen) instead of 0.50 g. per litre and containing per litre respectively 335 mg. tetraacetyl methylenediamine, 358 mg. triacetyl methylenediamine and 342 mg. of a mixture of these compounds, containing 67% tetraacetyl methylenediamine.

The relative improvements as to the lightness of the washed material, were in these cases, where 2.5 bound acetyl groups per atom of active oxygen were used, respectively, 186%; 83% and 181%.

EXAMPLE XIX

In order to illustrate the beneficial effect of covering an activator according to the invention with a solid material soluble in the washing and/or bleaching liquid, two comparative washing tests were carried out as described in Example I using suds, containing 0.61 g. of sodium perborate (9.9% of active oxygen) instead of 0.68 g. per litre, and respectively 401 mg. tetraacetyl methylenediamine and 401 mg. of the same compound but covered with a stearic-palmitic acid coating, per litre.

The coating amounted to 25% of the weight of the tetra-acetyl methylenediamine and consisted of a technical eutectic mixture of stearic and palmitic acid (M.P. 53-55° C.). The experiments were performed at 50° C.

The relative improvements as to the lightness of the washed material, were in these cases, where 2.0 bound acetyl groups per atom of active oxygen were used respectively 86% and 103%.

When applying a covered tetra-acetyl methylene di-amine, an increase in lightness of about 20% as compared with the non-covered compound was obtained.

When applying 275 mg. of tetra-acetyl hydrazine covered with 18% of carboxy-methylcellulose or 428 mg. of tetra-acetyl methylenediamine covered with 9% of cetyl-alcohol an increase in lightness of respectively 29% and 25% as compared with the corresponding non-covered compounds was found. Also in these cases the ratio

$$\frac{\text{Bound acetyl groups}}{\text{Atom of active oxygen}} \text{ was } 2.0$$

EXAMPLE XX

A washing test substantially as described in Example VIII was carried out but using 9.95 parts of N-caproyl-diacetamide instead of 5.96 parts of triacetamide and using 5.90 g. of the corresponding mixture per litre instead of 5.70 g. of mixture STrAA.

In this case where 2.0 bound acetyl groups per atom of active oxygen were used, the relative improvement as to the lightness of the washed material was 104%.

EXAMPLE XXI

Each of four different detergent compositions A, B, C and D contained:

35 12% non ionic detergent (isononylphenolpolyglycol-

ether, containing about 8 ethylene oxide groups in each molecule)

36% sodium tripolyphosphate

8% sodium silicate, $\text{SiO}_2/\text{Na}_2\text{O}$ ratio=2/1

50 2% commercial CMC, containing 50% sodium salt of carboxymethyl-cellulose

6.6% sodium perborate

Further these four compositions contained respectively:

55 Composition A: 4.12% tetra-acetylhydrazine

Composition B: 4.40% tetra-acetyl methylenediamine

Composition C: 5.50% coated tetra-acetyl methylenediamine, containing 80% tetra-acetyl methylenediamine as described in Example XIX

60 Composition D: no additional substances

In all four compositions the balance was sodium sulphate. In compositions A, B and C the ratio:

$$\frac{\text{Total meq. combined acyl groups}}{\text{Mg. at. active oxygen}}$$

was equal to 2.0:1.

All four compositions were used in a concentration of 5.00 g./l. for washing pieces of a cotton fabric, which had been soiled uniformly with black currant juice. After thoroughly rinsing with water, and ironing, the lightness (or apparent luminosity) of the fabric was 49.4 (lightness of magnesium oxide=100).

Pieces of this fabric were used for washing with the four detergent compositions A, B, C and D. After three times rinsing and ironing, their lightness was measured

by means of a photo-electric tristimulus reflectometer. The results are shown in the following table.

Temperature of treatment	Lightness of fabric pieces, washed and bleached in composition—			
	A	B	C	D
60°	68.1	68.2	70.4	
50°	72.2	72.5	73.7	60.4
35°	70.3	69.1	71.0	
18°	66.3	67.5	68.3	

In the following table, the improvements in the lightness, caused by the above-mentioned activators are expressed as percentages of the difference between the lightness of the fabric after rinsing with water only and the lightness of the material after treatment with detergent composition D at 50° C., as compared with the lightness of the latter.

Temperature of treatment	Percentage improvement of lightness. Treatment in composition—			
	A	B	C	D
60°	70	71	91	
50°	107	110	121	0
35°	90	79	96	
18°	54	65	72	

The same results are obtained, if the detergent compositions contain fluorescent brighteners, dyestuffs and/or perfumes. Essentially the same results are obtained with other kinds of fabrics, like wool, linen, silk, viscose rayon, acetate rayon, polyamide, polyester, polynitrile, polyvinyl and other natural and synthetic fibres. The same applies to the use of other non ionic surface active agents and other builders.

EXAMPLE XXII

Pieces of unbleached cotton fabric were boiled for 3 hours in a 1% solution of sodium hydroxide in water which had been softened by means of a cation-exchanger. Thereupon they were rinsed with softened water till the sodium hydroxide was almost fully eliminated. A sample of the treated fabric was dried (sample M) and the light remissions (diffuse reflections) were measured with the aid of a photo-electric remission-meter. The lightness (G) was 75.9% and the tristimulus blue and amber-remissions (B and A) were 65.6 and 78.8% respectively from those of magnesium oxide freshly precipitated from the vapour phase.

The yellowness, J, was 17.1 according to the formula from R. S. Hunter ("Photoelectric Tristimulus Colorimetry With Three Filters," Circular of the National Bureau of Standards C 429, U.S. Government Printing Office, Washington, 1942, p. 22):

$$J = \frac{A - B}{G} \cdot 100$$

The pieces of cotton fabric boiled with sodium hydroxide and rinsed with softened water were bleached for 15 minutes in the following ways:

- (a) At 60° with a solution containing 3.0 g. of anhydrous soda and 2.0 g. of sodium bicarbonate per litre and a quantity of hydrogen peroxide equivalent to an active oxygen content of 1.18 g. per litre of solution. At 20° the pH of the solution was 10.0;
- (b) At 82° with a bleaching liquid of the same composition as that mentioned under (a). At 20° the pH of this solution was 10.0;
- (c) At 60° with a bleaching liquid of the same composition as described under (a) and (b) but containing in addition 7.9 g. of TAMD (tetra-acetyl-methylene-diamine) and 2.62 g. of sodium hydroxide per litre. Thus a quantity of TAMD equivalent to 2 meq. acyl groups of TAMD per mg. at. active oxygen was added

to the bleaching liquid. At 20° the pH of this solution was 10.0.

After the bleaching process, the pieces of cotton fabric were rinsed with softened water and dried.

5 Measuring with the photo-electric remission meter gave the following remission-values:

Bleaching treatment	Temp., 0°	Tristimulus-remission values			Yellowness J
		G	B	A	
a	60°	79.5	67.8	82.5	18.3
b	82°	80.2	69.1	83.1	17.3
c	60°	86.1	78.5	88.9	11.9

15 While by bleaching with hydrogen peroxide without TAMD the yellowness calculated according to the formula from Hunter had hardly altered or even had somewhat increased, by bleaching in the presence of TAMD it decreased considerably.

Expressed in percentages of the difference between the remission values of the piece of fabric bleached according to treatment (a) and those of the unbleached sample M, the improvements of the remission values of the treated materials, as compared with those of the fabric bleached according to treatment (a) were:

Percentage Improvements

Bleaching treatment	Temp., 0°	Tristimulus-remission values		
		G	B	A
a	60°	0	0	0
b	82°	19	59	16
c	60°	183	487	173

Consequently the improvements by adding TAMD at 60° were 8 to 10 times as great as the improvements by increasing the temperature from 60° to 82° without TAMD.

The pieces of cotton fabric bleached according to method (c) contained considerably less seedrests than the pieces bleached according to the methods (a) and (b). Moreover, the cotton piece bleached in the presence of TAMD at 60° was much more hydrophilic than both other ones. A drop of water put on it was absorbed immediately.

EXAMPLE XXIII

50 A piece of unbleached cotton fabric was boiled for 1½ hours in a 1% solution of sodium hydroxide in water softened by means of a cation-exchanger. Subsequently it was boiled another 1½ hours in another, fresh 1% solution of sodium hydroxide in softened water. Thereupon it was rinsed with softened water till the sodium hydroxide was almost fully eliminated. A sample of the treated cotton fabric was dried (sample N) and the light remissions (diffuse reflections) were measured with the aid of a photo-electric remission-meter. The lightness (G) and the tristimulus blue and amber remissions (B and A) were 79.4, 73.3 and 81.3 respectively. Consequently, the yellowness according to the formula from R. S. Hunter was 10.0.

65 Various parts of the piece of cotton fabric boiled with sodium hydroxide and rinsed with softened water were put into one of the following eight bleaching liquids, thereafter heated in 10 minutes from 20° till the temperature for treatment mentioned hereafter and subsequently kept at that temperature for 15 minutes. Then the pieces of cotton fabric were rinsed with softened water and dried; subsequently their light-remissions were measured.

The compositions of the bleaching liquids, their temperatures and the results of the measurements are indicated in the following table.

30% H ₂ O ₂ , ml./l.	Composition of the bleaching liquid			Temp., °C.	End pH	Tristimulus-remission-values			Yellow- ness J	Percentage im- provements of the	
	Neutral water, g./l. (100%)	NaOH, g./l.	TAMD, g./l.			G	B	A		Light- ness G	Yellow- ness J
10-----	0	0	0	50°	8.0	82.2	75.4	83.4	9.6	0	0
10-----	0	0.53	3.78	50°	5.1	85.9	80.7	86.0	6.1	132	875
10-----	2.14	0	0	50°	9.8	84.0	76.7	84.2	8.8	64	200
10-----	2.14	3.18	3.78	50°	9.6	86.7	82.3	86.6	4.9	101	1,175
10-----	0	0	0	82°	7.6	86.8	82.0	86.9	5.6	164	1,000
10-----	0	0.98	3.78	82°	5.0	88.0	84.5	88.0	3.9	207	1,425
10-----	2.14	0	0	82°	9.7	86.6	81.6	86.8	6.0	157	900
10-----	2.14	3.10	3.78	82°	9.0	88.2	84.7	87.9	3.6	214	1,500

The improvements as to the remission-values and the yellowness of the bleached cotton fabrics are expressed in percentages of the difference between the corresponding values of the unbleached sample N and those of the piece of cotton fabric bleached without TAMD and without waterglass at 50° C., as compared with those of the latter.

The improvements due to the presence of TAMD in the bleaching liquid were most significant both at 82° and at 50° without and with waterglass. All pieces of cotton fabric bleached in the presence of TAMD do not contain any seedrests, in contrast to the cotton pieces bleached without TAMD.

In these tests, a quantity of TAMD equivalent to 0.75 meq. acyl groups of TAMD per mg. at. of active oxygen was present in the bleaching liquid. The concentrations of active oxygen and TAMD may be chosen both higher and lower whereby it is not necessary to stick to the value 0.75 for the above-mentioned ratio.

EXAMPLE XXIV

On measuring with a photo-electric remission meter, a woolen fabric gave the following light remission values: lightness (G) 72.3; tristimulus blue and amber remission (B and A) 57.7 and 74.8 respectively. Thus the yellowness (J) according to R. S. Hunter was: 23.5. Two parts of this fabric were bleached for 45 minutes at 35° in water softened with the aid of a cation-exchanger. Thereafter they were rinsed with softened water, dried and their light remission values were measured again.

Composition of the bleaching liquid	Bleaching treatment a	Bleaching treatment b
Hydrogenperoxide, g. of active oxygen/l.	1.412	1.412
TAMD, g./l.	0	9.440
NaOH, g./l.	0	3.12
End-pH	9.6	8.1
Lightness	75.0	77.5
Tristimulus blue-remission	60.9	63.9
Tristimulus amber-remission	77.1	80.0
Yellowness	21.3	20.5
Improvement by TAMD of the lightness	0	93%
Tristimulus blue-remission	0	94%
Tristimulus amber-remission	0	96%
Yellowness	0	36%

The improvements of the remission values and the yellowness are expressed again in percentages of the difference between the corresponding values of the unbleached fabric and those of the fabric bleached according to treatment a, as compared with those of the latter. So by using TAMD in the bleaching liquid, it is clear that the woolen fabric was bleached better.

The concentrations of active oxygen and TAMD may be chosen both higher and lower, whereby it is not necessary to stick to the ratio between the active oxygen- and activator-concentrations given above.

Instead of hydrogen peroxide in the Examples XXII-XXIV other compounds releasing active oxygen may be used, such as perborate, percarbonate, pyrophosphate-perhydrate. Instead of TAMD, also other activating agents

according to the invention may be used. The duration of the bleaching treatment may be chosen dependent on the bleaching and the activating agent concentrations, the temperature, the pH of the bleaching liquid and the improvement required. If desired a surface active substance may be added so as to accelerate wetting of the fabric.

EXAMPLE XXV

Pieces of cotton fabric, soiled with the juice of black currants as described in Example I, were treated according to one of the following three processes.

A. Washing for 10 minutes at 50° C. in suds containing:

	G./l.
Sodium soap	1.00
Sodium CMC (100%)	0.10
Sodium carbonate anhydrous	3.86
Neutral waterglass (100%)	0.36

After washing, the material was rinsed twice with water, first for 10 minutes at 50° C., subsequently for 3 minutes at 20° C.

B. Washing and bleaching for 10 minutes at different temperatures in suds of the same composition as described under A, but containing in addition:

	G./l.
Sodium perborate (10.2% active oxygen)	0.500
Tetra-acetylmethylenediamine	0.335

After washing and bleaching the material was rinsed twice with water, first for 10 minutes at the same temperature at which washing and bleaching took place, subsequently for 3 minutes at 20° C.

C. Washing for 10 minutes at different temperatures in suds of the same composition as described under A, followed by rinsing and bleaching simultaneously for 10 minutes at washing temperature with water containing:

	G./l.
Sodium perborate (10.2% active oxygen)	0.500
Tetra-acetylmethylenediamine	0.335

After this treatment the material was rinsed for 3 minutes at 20° C.

The lightness of the treated material is disclosed in the following table.

Process	A	B	C
Temperature of test in °C.	50	35	50
Lightness of treated material in units	58	65	70

Lightness of magnesium-oxide=100 units.

Of the above described acylated activator compounds, a preferred group are those compounds having the formula:

17

wherein X is selected from the group consisting of phenyl, an aliphatic acyl group having 1 to 6 carbon atoms in the aliphatic chain, a lower alkyl, a

group in which R_1 represents a lower alkylene group, and R_2 is selected from the group consisting of hydrogen and acetyl, and a

where R_2 is as defined above.

EXAMPLE XXVI

The tetra- and tri-acetyl methylenediamine or mixtures of these compounds used in the experiments as described in the Examples XIV-XIX and XXI-XXV were prepared as follows:

Preparation of *N,N'-Tetra-Acetylmethylenediamine*

A. 200 g. of *N,N'-diacetylmethylenediamine*, which may be prepared from acetamide and paraformaldehyde, were suspended with stirring in 1500 cc. dry benzene. After addition of 4 g. *p*-toluene-sulphonic acid as a catalyst, ketene was introduced until all the *N,N'-diacetyl-methylenediamine* had gone into solution which occurred within 7 hours, at 50°-65° C. Thereupon, the reaction mixture was cooled in ice; 159 g. of TAMD crystallized; melting-point 95°-96° C. By concentrating the mother liquor to one fourth volume and cooling, another 137 g. of *tetra-acetylmethylenediamine* were obtained.

B. 325 g. (2.5 mols) *N,N'-diacetylmethylenediamine* (M.P. 200-200.5° C.) is dissolved by heating in 1530 g. (15 mols) acetic acid anhydride (98%). With the help of a fractionating column the acetic acid formed during the reaction is distilled off simultaneously at a bottom temperature of 140-145° C. in a period of 14 hours.

The reaction comes to an end when the distillate has reached the boiling point and refractive index of pure acetic acid anhydride.

The distillate amounting to 425 g. contains 330 g. acetic acid.

By distillation under reduced pressure all the acetic acid anhydride still present in the reaction mixture is removed yielding 523 g. crude product (theor. 535 g.).

After recrystallization from 523 cc. isopropyl alcohol 480 g. (=2.25 mols) pure *tetra-acetylmethylenediamine*, M.P. 95-96° C., is obtained.

Preparation of *N,N,N'-Tri-Acetylmethylenediamine*

325 g. (2.5 mols) *diacetyl-methylenediamine* (M.P. 200-200.5° C.) is dissolved by heating in 3060 g. (30 mols) acetic acid anhydride 98%. After boiling under reflux for 4 hours the acetic acid/acetic acid anhydride mixture is removed under reduced pressure yielding 433 g. of a slowly crystallizing product. By recrystallization from 433 cc. isopropyl alcohol 359 g. (2.09 mols) of *tri-acetyl-methylenediamine* (M.P. 83-84° C.) is obtained.

Preparation of a Mixture of *Tri- and Tetra-Acetyl-methylenediamine*

325 g. (2.5 mols) *diacetyl-methylenediamine* (M.P. 200-200.5° C.) is dissolved by heating in 1530 g. (15 mols) acetic acid anhydride 98%.

With the aid of a fractionating column 160 g. of acetic

18

acid is distilled off during the reaction at a bottom temperature of 140-145° C. in 4 hours.

From the reaction mixture the solvents are distilled off under reduced pressure yielding 490 g. crude product containing besides *tri-acetyl-methylenediamine* also *tetra-acetyl-methylenediamine*.

By fractional distillation under reduced pressure 148 g. *tri-acetyl-methylenediamine*, B.P. 129-131° C. at 2 mm. Hg and 301 g. *tetra-acetyl-methylenediamine*, B.P. 138-140° C. at 2 mm. Hg could be isolated from the crude product.

The invention is not limited by the above-mentioned examples, as within the scope of the invention various modifications will be possible. The activators may, e.g., successfully be employed in dishwashing agents which contain besides an anionic or a cationic or a non-ionic surface-active substance, also an active oxygen releasing compound, so that coffee, tea, chocolate, lipstick and similar spots may be removed more easily. It will also be possible to incorporate the activators in, e.g., bottle-washing agents, in agents for cleansing breweries, dairy and other food-processing factories, etc., whenever these agents contain an active oxygen releasing compound.

What is claimed is:

- 25 1. A textile treating composition consisting essentially of an active oxygen releasing compound selected from the group consisting of inorganic perborates, percarbonates, perphosphates, persilicates, persulfates, and peroxides and an activator compound selected from the group consisting of *N,N,N'N'-tetra-acetyl hydrazine* and *N,N,N'N'-tetra-acetyl-methylenediamine*, the said activator compound being present in such a quantity as corresponds to 0.5-4.0 nitrogen bound acetyl groups per atom of active oxygen in the active oxygen releasing compound.
2. A composition according to claim 1 wherein said active oxygen releasing compound is sodium perborate.
3. A composition according to claim 1 wherein said activator compound is *N,N,N'N'-tetra-acetyl hydrazine*.
- 40 4. A composition according to claim 1 wherein said activator compound is *N,N,N'N'-tetra-acetyl-methylenediamine*.
5. A composition according to claim 1 wherein said activator is in finely divided form covered with 1-30% of its weight by a material selected from the group consisting of stearic acid, a solid polyethylene glycol having an average molecular weight of 3000-3700, a solid polyethylene glycol having an average molecular weight of 6000-7500, carboxymethylcellulose and cetyl alcohol.

UNITED STATES PATENT OFFICE
CERTIFICATE OF CORRECTION

Patent No. 3,163,606

December 29, 1964

Wilhelmus J. C. Viveen et al.

It is hereby certified that error appears in the above numbered patent requiring correction and that the said Letters Patent should read as corrected below.

Column 9, line 39, the second table, under the column heading "5", line 3 thereof, insert -- 50 --; column 12, line 12, for "275" read -- 375 --; columns 15 and 16, the first table, under the column heading "B", line 6 thereof, for "84.5" read -- 84.6 --; same column 15, EXAMPLE XXIV, in the table, under the column heading "Bleaching treatment b", line 2 thereof, for "9.440" read -- 9.44 --.

Signed and sealed this 22nd day of June 1965.
